TELEVISION APPARATUS AND METHOD

Leslie A. Gould, Bridgeport, Conn., assignor to
Radio Inventions, Inc., New York, N. Y., a corporation of New York

Application January 23, 1932, Serial No. 588,333

2 Claims. (Cl. 178—7.6)

The present invention relates to a method and apparatus for scanning an optical image, as in television reception or transmission or the like.

One object of my invention is to secure an image of greater brilliance than has been heretofore commonly obtained by the use of a gas glow tube.

Another object of my invention is to secure a large image in relation to the size of the apparatus used.

A further object of my invention is to secure a scanning mechanism which requires only a low degree of accuracy for its manufacturing, and is consequently inexpensive to make.

A still further object of my invention is to secure a form of glow tube and method of operating the same, capable of very faithful modulation and consuming a relatively small amount of power in the glow tube.

Another object of my invention is to secure a scanning apparatus by which the image may be viewed directly or may be projected upon a screen at will.

My invention attains the above objects by utilizing a novel combination of a glow tube disposed in a helical configuration and located within a rotatable cylinder or drum, the drum for example being punctured with a series of regularly spaced apertures arranged in juxtaposition to the helical glow tube within, and includes suitable electrical circuits for supporting a picture signal to the glow tube.

Several forms of apparatus of my invention may be more easily understood by reference to the drawings forming part of this specification.

Fig. 1 is a view in elevation, representing the mechanical and optical portions of one form of the apparatus of my invention.

Fig. 2 shows in plan view a detail of a part of Fig. 1, namely the commutator for connecting in the proper order the picture signal to each turn of a two-turn glow tube.

Fig. 3 is a schematic diagram illustrating one form of electrical circuits for generating a picture-modulated high-frequency current to be delivered to the glow tube.

Fig. 4 is a plan view of a commutator for connecting in the proper order the picture signal to each convolution of a three-turn glow tube.

Figs. 5 and 6 illustrate alternative forms of my invention utilizing selective screening, instead of selective illumination.

Referring now to Fig. 1, a drum 11 is shown, constructed preferably of Bakelite or other insulating material having considerable mechanical

strength, reinforced by metal band 12 and mounted in flanged floor plate 13. This floor plate may be arranged to be rotated by a motor 21 (preferably of the synchronous type) through motor shaft 20, gear 19 fixed thereon, engaging gear 18 fixed upon shaft 15 which is supported in bearings 16 and 17, and carries floor plate 13 mounted thereupon by means of flanged collar 14.

To the inner surface of drum 11 is fixed by means of clamps 23 or other suitable means a 10 helical glow tube 22 made of glass tubing or other suitable transparent insulating medium bent to shape, provided with a plurality of suitable electrodes spaced approximately 360° apart along its length, and enclosing a gaseous medium capable 15 of a glow discharge under electrical excitation, such as neon, helium, mercury vapor or the like. Any mechanical unbalance of the system when rotating may be corrected by means of small weights 11' secured to drum 11 at proper points 20 to correct for any unsymmetrical placement of tube 22 giving rise to kinetic unbalance of the rotating system.

A plurality of substantially equally spaced apertures 24 (preferably of rectangular shape and 25 having bevelled edges) are disposed in the form of a helix about the drum 11 and coordinate with glow tube 22 to allow the emergence of its light therethrough.

The action of the helix of apertures is to scan 30 the image being reproduced, so that an observer viewing the drum 11 will see a plurality of images spaced adjacent to one another about said drum. A framing stop 25 with a suitable opening 26 may be placed close to the drum to limit the 35 view to a single complete image, or several observers may view different substantially complete images at different positions.

As hereinafter shown and described, the helical tube itself may serve to vertically delimit a 40 single elemental area, so that vertical slits may be cut in the drum, instead of apertures 24.

Motor 21 may conveniently have its phase relationship and angle of mechanical lag controlled by switch 70 and rheostat 71, although 45 other suitable means may be employed for this purpose.

In one form of the apparatus of my invention here described, a helix of two complete turns (720°) is used, but a greater number of turns or 50 a single turn may be used. The size of the area scanned is obviously increased by increasing the number of turns, other factors remaining equal.

Referring now to Figs. 1 and 2, the picture signal carrying conductors may be connected to 55

each turn of glow tube 22 in succession by means of any suitable commutator system of which one form is here illustrated. The central electrode of this glow tube may be "grounded" conductively to floor plate 13 by means of lead 27 and lug 28. A high tension lead 29 conducts current from the source of the picture signal to a stationary brush 30 which is supported in an insulating brush holder 31 and bears upon slip ring 32, the slip ring acting as the external portion of the commutator 33. The inner surface of the commutator is provided with a 180° insulating segment 34 of fibre or similar material and a 180° conducting segment 35 which is integral with the body of the commutator. Commutator 33 is concentric with shaft 15 and revolves in the same direction as, and at one-half the angular speed of the shaft. Shaft 15 is provided with a longitudinal central channel 36 for carrying distribution leads 37 and 38 from the commutator location to the electrodes of the glow tube. Two insulating brush holders 39 and 40 are spaced 180° apart and fixed to shaft 15, their brushes 41 and 42 bearing upon the inner surface of commutator 33 and being connected to distribution leads 37 and 38. Thus when the apparatus is in operation, the conductors carrying the picture signal are connected alternately to each turn of the helical glow tube, and remain in contact with each during one revolution of shaft 15.

If the source of picture signal delivers a modulated high-frequency current, stationary brush 30 may be replaced by a stationary capacity element or conducting plate in close proximity to slip ring 32, current transfer being then effected through the agency of the capacity existing between the conducting plate and said slip ring, or other methods of energy transfer, such as induction or radiation may be employed for this purpose.

Referring again to Fig. 1 certain possible methods of mounting and of rotating commutator 33 are illustrated. This commutator may be supported by an insulating ring 43 which is in turn supported upon gear 44 rotatably mounted on shaft 15 by means of bearing 45. Gear 44 engages a gear 46 fixed to motor shaft 20, the ratio of these gears being calculated from the rotational speed requirements given above.

Referring to Fig. 3, a thermionic vacuum tube 47 is there shown as arranged to produce sustained high frequency oscillations through the agency of reactors 48 and 49 in its grid and plate circuits, respectively, these reactors being mutually coupled with one another. Glow tube 22 with its associated commutator 33 may be positioned in series with the plate reactor 49 and with a capacitor 50, all these reactors and capacitors being chosen of such values as to possess substantially equal reactances to currents of the frequency generated, so as to compose a series resonant circuit. A variable capacitor 51 may be bridged across capacitor 50 and glow tube 22 for the purpose of independently increasing the current through reactor 49, thus increasing the amplitude of oscillation. The addition of this variable capacitor 51 may make necessary a different value of series capacitor 50.

Oscillating tube 47 may be arranged to be modulated by a picture signal (as from a receiver) through the thermionic tube 52 acting as an amplifier and modulator by the agency of a reactor 53 in its plate circuit. The modulating voltage appears across reactor 53 and may be conducted to the plate circuit of oscillator tube 47 through

reactor 54, according to the familiar Heising system with parallel feed. The filaments or cathodes of tubes 47 and 52 may be heated by current from any suitable source as from a transformer 55, the electrical center of said source being conductively connected to the proper circuits of said tubes. Batteries 56, 57 and 58 or other sources of substantially continuous current may supply the proper potential to certain of the circuits of said thermionic tubes employing such continuous current.

Fig. 4 shows one form of commutator which can be used with a spiral gas tube of three turns. In this figure a 120° insulating segment 65 is shown, interposed between a 120° conducting segment 66 which is insulated from the body 35 of the commutator as by an appropriate sheet 66' of insulation and is connected ("grounded") to shaft 15, and a 120° conducting segment 67 forming an integral part of the commutator body 33'. The external face of commutator body 33' is formed into a slip ring 32'. Three equally spaced brushes 68 bear upon the commutator and are supported on shaft 15 by insulating brush holders 69.

A three-turn helical glow tube (not shown) would have the electrodes at its ends connected together as one terminal and a single lead brought down from this connection to a brush 68 (Fig. 4). The two intermediate electrodes are each connected through a lead to one of the other two brushes 68, in the proper sequence.

The voltage applied may be so adjusted that it is sufficient to "break down" a single turn of glow tube 22 to which it is applied, but will not break down the other two turns which are effectively in series. The commutator should revolve in the same direction as the scanning drum, and at % the rotational speed of the latter.

Helical glow tubes of any number of turns may be operated similarly, the number of brushes and of commutator segments each being equal to the number of turns in the helix. Two adjacent commutator segments should be conducting, and the remainder insulating as in the case of a three-turn helix. The ratio of the rotational speed of the commutator to the rotational speed of the scanning drum should be

$$\frac{N-1}{N}$$

where N is the number of turns in the helical glow tube, and the rotational direction of the commutator should be the same as that of the drum.

In the operation of small sized apparatus according to this invention I have observed that thermionic tubes 47 and 52 may be of 7½ watt rating or smaller and yet be very successful in operation and that a high-frequency current of 10 milliamperes through glow tube 22 is usually sufficient to produce a comparatively brilliant illumination. Since this glow tube is in close proximity to apertures 24 its light is effectively utilized, i. e., is directly available for viewing from a point outside of the drum 11 without certain losses common to systems in which the glow tubes are remote from the scanning apertures.

I prefer to use a gas column type of glow tube, i. e., a tube having a glow discharge in a relatively uniform and narrow column from the point of current entrance to the point of current exit. I have found the best in uniformity and brilliance of glow and the best modulating characteristics are obtained when using a high-frequency current

in the tube, modulated with the picture signal. However, I have also operated the glow tube directly from the picture signal, it being usually preferable to provide a component of continuous current through the glow tube for the latter system.

Drum 11 may be of metal when using this latter system, but when using the high frequency system certain capacity effects such as that from the glow tube to the drum may make such metallic construction inadvisable.

The image may be viewed by any one of three methods, namely, (1) viewing the image at the drum directly or through a magnifying lens, (2) projecting the image from the drum to an opaque screen by means of a lens, or (3) projecting the image from the drum to a translucent screen. These methods may be used interchangeably, as will be described below.

Assuming that the image is to be scanned from left to right and progressively downward, and is to be viewed directly at the drum, the direction of winding of the helical glow tube and the direction of rotation of the drum should be as shown in Fig. 1.

As the drum revolves, the upper turn of glow tube 22 being lighted, each aperture 24 moves across the field of view and produces one line of the image, successive lines being displaced downward by the width of one line. When drum 11 has completed one revolution the lowest aperture 24 in the upper turn of glow tube 22 has passed across the field of view. Commutation now occurs and the lower turn of the glow tube is lighted, scanning continuing downward. When drum 11 has completed the second revolution, commutation again occurs and the upper turn of the glow tube is lighted. This cycle is repeated at a rate greater than the persistence of vision and an image having apparent motion may be seen through viewing aperture 26.

A magnifying lens 64 may be placed before the drum to enlarge the apparent size of the image without reversing the horizontal or vertical relation of the image to an observer.

If, however, the image is to be projected upon a translucent screen through a focusing lens it becomes necessary to re-invert it (since the focusing lens acts to invert it) which may be accomplished by properly placing two inclined mirrors (or a single prism) in the optical path between the drum and screen and properly placing the screen. The enlarged image will then be viewed from the side of the translucent screen opposite the focusing lens, and will appear in the proper horizontal and vertical relation.

If the image is to be projected upon an opaque screen through the focusing lens it becomes necessary to re-invert the image (after inversion by the lens) and to reverse it in the right and left direction, which may be accomplished by two pairs of inclined mirrors, inclined upon axes at right angles to one another. Likewise two prisms may be used, as is familiar in the construction of certain field or opera glasses.

In case it is desired only to view the image at the drum (through a magnifying lens), the glow tube 22 may be constructed with a pitch relatively greater in the ratio that the image is to be magnified, and a cylindrical magnifying lens used in place of lens 64, with its axis parallel to the axis of drum 11. It may be an advantage to increase the pitch of helical glow tube 22 for the sake of ease in construction and then magnify in one dimension only.

It is understood that any desired size and ratio of the component parts of the apparatus of my invention may be used without departing from the field of my broad invention, but the following example will illustrate a possible construction.

For receiving a visual image scanned with 60 lines at 20 pictures per second, scanning being from left to right and progressively downward, the helical glow tube 22 of Fig. 1 may be wound as in a right hand screw, and the drum 11 revolved so that the side nearer an observer moves from left to right. There should be 60 apertures 24 and these apertures should be spaced 12 angular degrees apart around the drum. The pitch of the helical glow tube 22 may be such that the axial distance from the uppermost aperture in the helix to the lowest aperture in the helix is somewhat less than the peripheral distance between any two adjacent apertures, according to the ratio of image height to width desired. The rotational speed of drum 11 should be 2400 R. P. M., and the rotational speed of commutator 33 should be 1200 R. P. M., a speed ratio of 2:1. Framing of the image in viewing aperture 26 may be effected by means of a switch 70 and variable resistor 71 in the motor supply line. When the apparatus is operating, varying the resistor 71 causes the image to move horizontally, and momentarily opening switch 70 causes the image to move vertically. Proper manipulation centers the image in aperture 26.

Another framing method, such as producing a plurality of images and moving a selective framing aperture, may be employed, as well as other suitable methods familiar in the art.

If a single-turn helical glow tube 22 is used, no commutation is necessary, and a single slip ring may be mounted upon shaft 15 for conducting the picture signal to the glow tube.

The drum 11 may be eliminated if desired, and the helical glow tube 22 mounted in other supporting means. The glow tube may then be coated with an opaque layer of black enamel or other suitable material, in which properly spaced light apertures are produced, as by grinding, scraping or otherwise removing the enamel.

In Fig. 5, motor 101, on support 102, rotates drum 103, containing helical gas tube 104, receiving current through electrodes at each end thereof. One end may conveniently be grounded to the metal frame work which may be connected to the low-potential terminal of the signal supply by lead 105 while the other end may be connected to slip ring 106, upon which bears brush 107, connected by lead 108 to the high-potential terminal of the signal supply.

Drum 103 may be provided with slits 109 or the perforations of the previously described forms may be employed. Without drum 103 and concentric therewith, rotates drum 110, driven by gear 111. Idler gear 112 fixed to idler gear 113, both rotatable upon fixed shaft 116 and driven by gear 114 upon the motor shaft, rotates drum 110 at a speed less than that of drum 103, in this case at one third the speed.

Drum 110 is provided with horizontally disposed slots 115 which may be equal in number to the number of convolutions of tube 104, which serve to allow the viewing of only a single turn of tube 104 at any one instant.

By this construction the use of selective illumination of portions of the gas tube is avoided, and selective screening of the illumination of the totality thereof is employed to replace the same.

In Fig. 6, the motor, the spiral gas tube and its drum, and the mode of current conduction thereto may be similar to the corresponding parts in Fig. 5. Apertures 209 are shown in this form, but slits like those of Fig. 5 may be used without other change.

A second scanning drum 210 is driven by sprocket 211, deriving its motive power through bevel gear 212 from the motor 201 by means of shaft 216, bevel gears 217 and 218, and shaft 219. Drum 210 rotates at a speed S which is preferably an integral fraction of the motor speed and such that speed S in revolutions per second equals the number of pictures per second divided by the number of slits 215.

Slits 215 on drum 210 are moved at right angles to the spiral tube drum 203, and fulfill substantially the same screening functions as the slits 115 of Fig. 5. Mirror 231, supported within drum 210 by means of bracket 230 at approximately 45°, may serve to project the scanned light rays without the drum and in a direction substantially parallel with the axis thereof.

The forms of Figs. 5 and 6 may be subjected to the same modifications as those of the first described form of my invention, such as would be apparent to those skilled in the art.

For example, the screening slits may be located upon a disc or belt instead of the drums here shown.

By suitable substitutions familiar to one skilled

in the art, such as the substitution of a helical light sensitive cell for the glow tube, my invention may be used for transmission scanning.

It is understood that the apparatus of my invention may be subject to many other changes, as will be obvious to one skilled in the art, without exceeding the scope of my broad invention which is limited only by the appended claims.

I claim:

1. Television scanning apparatus including a helical glow tube having all its turns of equal radii rotating about its axis, a screening member rotating therewith and exposing a plurality of elemental areas of discrete turns of said tube at one instant, and a separate screening member rotating in synchronous relationship with the first mentioned screening member and screening all but one of said elemental areas at any one instant. 10

2. A television scanner including two drums provided with suitable slits upon their peripheries and rotating at right angles to each other, one of said drums enclosing and rotating therewith light producing means responsive to television signals and disposed in helical forms, said rotation of the helical light producing means cooperating with the rotation of the enclosing drum thereof to scan an optical image at a plurality of points simultaneously, and the other drum cooperating by its rotation so that only one of said plurality of scanning points shall be visible at one instant. 20
